DESIGN FOR A FIGURETTE LAPEL PIN

William R. P. Wilson, Springfield, S. C.

Application April 14, 1948, Serial No. 145,711

Term of patent 14 years

(Cl. D45—19)

To all whom it may concern:

Be it known that I, William R. P. Wilson, a citizen of the United States of America, residing at Springfield, South Carolina, county of Orangeburg, have invented a new, original, and ornamental Design for a Figurette Lapel Pin, of which the following is a specification, reference being had to the accompanying drawing, forming a part thereof wherein:

I claim:

The ornamental design for a figurette lapel pin, as shown.

WILLIAM R. P. WILSON.
